UNITED STATES PATENT OFFICE.

DAVID PERRY, OF ST. PAUL, MINNESOTA.

DENTAL CASTING-MACHINE.

1,280,289.

Specification of Letters Patent. Patented Oct. 1, 1918.

Application filed January 26, 1913. Serial No. 214,084.

To all whom it may concern:

Be it known that I, DAVID PERRY, a citizen of the United States, residing at St. Paul, in the county of Ramsey and State of Minnesota, have invented certain new and useful Improvements in Dental Casting-Machines, of which the following is a specification:

This invention relates to improvements in dental casting machines of the type wherein the molten material is projected into the recesses of the mold by centrifugal action, and wherein the revolving element rotates in a horizontal plane. One of the objects of my invention is to provide a machine extremely simple in construction, avoiding all the usual adjustment screws and machined parts, and still retain with increased practicability, certain salient features desirable in the art.

A further object is to provide a machine, economic in its usage, whereby a saving of heat and of material used in preparing the molds, and material to be cast therein, is effected.

The invention consists in the construction, combination and arrangement of parts illustrated in the drawings and described in the specification of which the drawings form a part:

Referring to the drawings,

Fig. 1 is a perspective view of the centrifugal casting mechanism of a dental casting machine,

Fig. 2 is a side view of the same partly in section.

Fig. 3 is a section on line 1—1 of Fig. 1, and

Fig. 4 is a sectional fragmentary view of details.

Fig. 5 is a sectional side view of a mold.

In the drawings, Fig. 1 represents the centrifugal element of a dental casting machine, the actuating element for said centrifugal element not being shown.

The rotating element comprises a cross-beam 2, shaped at one of its outer ends to form a semi-cylindrical mold ring cradle 3 or main cradle, open at its top and inner end but closed at its outer end by a vertical wall 4. The longitudinal axis B of the cradle is parallel to, and lies above that of the cross-beam 2. On the beam 2 and adjacent to the open inner end of the cradle 3 is a crucible support 5, comprising a horizontal platform 7 having longitudinal side walls 8 wherein the crucible 9 is loosely and slidably contained. The crucible 9 is formed

with a reservoir 10 and a discharge opening 11, the crucible support 5 being arranged so that the reservoir 10 will be below, and the center of the discharge opening 11 will coincide with the axis B, and so that the crucible may be freely slid to and fro on the platform, along the line of the axis B.

The cross-beam 2 is formed at its other end with a counter-weight 12. Removably supported on the upper edges of the cradle 3 and concentric therewith, is an auxiliary cradle 13, having lateral arms 14 and down-turned flanges 15 at their outer ends to control the auxiliary cradle 13 so that the axis 70 of its semi-cylindrical portion will coincide with the axis B.

One of the flanges 15 is provided with a finger piece 16 whereby the auxiliary cradle may be grasped and removed as may be desired.

Referring to Fig. 2 of the drawings, I have shown one of a plurality of mold rings 17 lying in the main cradle 3 and fitting loosely therein, the longitudinal axis of both, 80 coinciding and registering with the discharge opening in the crucible. Shown in dotted lines in the same view are two auxiliary cradles 13 and 13^a of varying size (of which there may be any number) all registering 85 centrally, with the crucible opening 11.

The cross-beam 2, together with the mold ring and cradle is poised as a unit, through the medium of stud 18, on actuating devices, (not shown) said stud being rigidly secured 90 on the cross-beam 2.

To maintain an even balance in the whole rotating element, regardless of the use of any of the interchangeable mold rings and auxiliary cradles, the rings and auxiliary 95 cradles are made of proportionately thicker metals (shown in Fig. 4) to compensate in weight for the variations in size.

In use, when a large mold is required, the ring containing the mold (Fig. 2) is placed 100 in the main cradle 3 and the crucible with its discharge opening is slid against it.

The metal in the crucible reservoir is now melted by the usual use of a blowpipe, when the whole device is rapidly rotated in a horizontal plane (the wall 4 sustaining the mold ring) and the molten metal projected, by centrifugal force through the discharge opening 11 into the mold recesses.

The molds are formed by casting the investment material C into the mold ring around a pattern made of wax. When the

cast is thoroughly dry, intense heat is applied wherethrough the wax pattern is melted out of the mold cavity.

When an unnecessarily large mold ring is used for a very small casting, it requires considerable time to sufficiently heat the large mass of material, which infrequently develops cracks (Fig. 6), because of its excessive thickness around the mold cavity.

10 Obviously the advantage of a centrifugal mold machine, wherein several sizes of mold rings may be used, is therefore very important.

To salvage metal escaping through cracks 15 in mold (Fig. 6) I provide an annular flange 19 on the outer wall 4, whereby the escaping metal is detained until cooled.

I claim:

1. In a centrifugal element of a dental 20 casting machine, in combination with the cross beam and its counterweight, of a main mold ring carrier having an arcuate bottom and integral with said cross beam and opposite said counterweight, and an auxiliary 25 mold ring carrier having an arcuate bottom of smaller curvature than said first named mold carrier and concentric with the bottom of the latter and removably resting thereon.

2. In a centrifugal element for dental 30 casting machines, the combination with the cross beam and its counterweight, of a main semi-cylindrical open top mold ring cradle on said cross beam and having its longitudinal axis parallel therewith and an auxiliary 35 open top mold ring cradle insertible from above downwardly to loosely and slidably rest on the upper edge of said main mold ring cradle and having its longitudinal axis coincide with the axis of the latter for the 40 purpose specified.

3. In a centrifugal element for a dental casting machine, in combination with the cross beam, of a counter-weight rigidly fixed at one end of the cross beam and a main 45 comparatively large open top mold ring support adapted to hold a mold ring rigidly fixed at the opposite end of said crossbeam,

a support between the ends of the cross beam arranged thereon to effect a state of equilibrium therein, when there is a mold in said main mold ring support, and a smaller auxiliary mold ring support adapted to hold a smaller mold than said main mold ring support and loosely and removably resting on the latter, said auxiliary mold ring support being so proportioned in weight as to maintain said state of equilibrium in the cross beam when the larger mold is removed from said main mold ring support and the auxiliary mold ring support holding the smaller 60 mold is inserted.

4. In a centrifugal element for a dental casting machine, in combination with a one piece counter-balanced cross beam supported between its ends comprising a cradle opposite the counterweight and adapted to hold a mold of certain weight removably fitting said cradle, said cross beam being in a state of equilibrium on its support when supporting said mold, and an independent cradle insertible in said first named cradle and adapted to contain a mold of lesser weight than said first named mold, the combined weight of said independent cradle and its mold being approximately equal to the weight of 70 said first named mold for the purpose of maintaining said state of equilibrium in the cross beam.

5. In a centrifugal element of a dental casting machine, in combination with the 80 cross beam and its counter-weight, of an open top mold ring support on said cross beam opposite said counter-weight, and an auxiliary open top mold ring support insertible in the open top of the first named 85 mold ring support and removably resting thereon.

In testimony whereof I affix my signature in presence of two witnesses.

DAVID PERRY.
